CASE FOR CREDIT PLATE

George A. Gazan, Jr., Ferndale, Mich.

Application November 16, 1950, Serial No. 13,016

Term of patent 14 years

(Cl. D87—3)

To all whom it may concern:

Be it known that I, George A. Gazan, Jr., a citizen of the United States, residing at Ferndale, in the county of Oakland and State of Michigan, have invented a new, original, and ornamental Design for a Case for Credit Plate, of which the following is a specification, reference being had to the accompanying drawing, forming part thereof.

Fig. 1 is a front perspective view of a case for credit plate showing my new design,

Fig. 2 is a top plan view of the case for credit plate,

Fig. 3 is a side elevational view of the case for credit plate,

Fig. 4 is an end view of the closed end of the case for credit plate, and

Fig. 5 is an end view of the opened plate receiving end of the case for credit plate.

The characteristic feature of my design resides in the combination with a rigid envelope type case having a peaked tab portion, of a raised crown portion upon the upper envelope wall with a concave peripheral groove around the closed parts thereof, as shown.

I claim:

The ornamental design for a case for credit plate, as shown and described.

GEORGE A. GAZAN, JR.
